Fig. 1.

Fig. 2.

Fig. 3.

Fig. 4

Fig. 5

FIGURE 1 is a perspective view of a building showing my new design;

FIGURE 2 is a left side elevation view thereof;

FIGURE 3 is a front elevation view thereof;

FIGURE 4 is a top plan view thereof; and

FIGURE 5 is a view taken along the lines 5—5 in FIGURE 2.

A back elevational view of the building is substantially the same in appearance as the front elevational view thereof shown in FIGURE 3 except for the omission of the door.

A right side elevational view of the building is substantially the same as the left side elevational view thereof shown in FIGURE 2 except for the omission of the door.

I claim:

The ornamental design for a building, substantially as shown and described.
